Primary Examiner — Ian Simmons*Assistant Examiner* — Shannon Morgan(74) *Attorney, Agent, or Firm* — Edward J. Baba; Bozicevic, Field & Francis LLP(57) **CLAIM**

The ornamental design for a juice extractor, as shown and described.

DESCRIPTION

FIG. 1 is a top, front perspective view of a juice extractor, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a top, left perspective view thereof.

The broken lines shown in FIGS. 4 and 7 represent portions of the juice extractor that form no part of the claimed design.

1 Claim, 7 Drawing Sheets(56)
